UNITED STATES PATENT OFFICE

HARRY ALTON DAVOL, OF METHUEN, MASSACHUSETTS, ASSIGNOR, BY MESNE ASSIGNMENTS, TO U. S. BOBBIN & SHUTTLE COMPANY, 1929, OF PROVIDENCE, RHODE ISLAND, A CORPORATION OF RHODE ISLAND

YARN TENSION FOR SHUTTLES

Application filed October 12, 1928. Serial No. 312,040.

This invention pertains to loom shuttles and more particularly to yarn tension devices for such shuttles. In my copending application Serial No. 249,640, filed Jan. 5, 1928, I have described a desirable type of tension in which the relatively movable tension elements are carried by a block adapted to seat in a cavity in the shuttle body. The present invention relates to a tension device of the same general type but of improved and greatly simplified construction, readily applicable to shuttles such as are used in duck looms in which the threading slot is formed in the wood of the shuttle body, and providing wear-resistant but readily replaceable tension elements which, if desired, may be so designed as to remain in substantially parallel relation while the yarn is passing between them.

In the accompanying drawings in which a desirable embodiment of the invention is disclosed by way of example,

Fig. 1 is a fragmentary plan view of a shuttle showing the present invention applied thereto;

Fig. 2 is a fragmentary side elevation of the same shuttle;

Fig. 3 is a side elevation showing a preferred form of tension means removed from the shuttle body;

Fig. 4 is a front elevation of the tension means of Fig. 3; also illustrating its cooperation with a modified type of yarn delivery eye;

Fig. 5 is a vertical section substantially on the line 5—5 of Fig. 1;

Fig. 6 is a plan view illustrating one desirable form of tension element;

Fig. 7 is a side elevation similar to Fig. 3 but showing a slightly modified arrangement of parts; and

Fig. 8 is a front elevation of the tension device of Fig. 7 associated with a guide eye such as shown in Fig. 4.

Referring to the drawings, the numeral 1

designates the body of a shuttle having a chamber 2 for the bobbin and a nose portion 3 provided with a chamber 4 for the reception of the tension devices. A substantially horizontal thread delivery passage leads from the chamber 2 forwardly into the nose portion 3 of the shuttle body, and thence extends laterally to the thread guide eye indicated at 5. This guide eye, in the embodiment shown in Fig. 2, is provided at opposite sides with wear-resistant posts 5^a of steel or porcelain as is usual and merges into the lower part of the tension-receiving chamber 4. A threading slot 6 extends from the bobbin chamber 2 forwardly and then laterally, terminating, if desired, immediately above the thread guide eye 5. The slot 6 opens at its lower portion into the horizontal thread delivery passage above referred to.

The thread tensioning means herein disclosed consists of a block 7 adapted to seat within the cavity 4. This block may be made of steel or other suitable material and is shaped to fit snugly within the cavity 4, being provided near one side with a bore for the reception of a bolt 8 whose lower end has screw-threaded engagement with a nut 9 seated in a bore 10 extending up from the bottom of the shuttle body. Preferably the block 7 is of more or less rectangular form, having its rear face rounded concentrically with the bore which receives the bolt 8 although the exact shape of the block is not essential.

The block 7 is provided with forwardly extending arms 11 and 12 respectively, the latter being at the bottom of the block while the arm 11 overhangs the arm 12 and preferably terminates in a downwardly extending portion 13 having a curved outer surface which is opposed to but spaced from the wall of the threading slot 6.

The block 7 is provided with a recess 14 for receiving the tension elements. Preferably this recess is arched at its top, the arm 11 hav-

ing a curved under surface which merges with the outer surface of the part 13 of the arm to provide a thin lower edge for the latter. This lower edge of the arm 13 is spaced from the 5 arm 12 so as to provide an opening leading in a forward direction from the recess 14 into the threading slot 6. The recess 14 is also open at opposite sides of the block into the horizontal thread passage above referred to.

10 The arms 11 and 12 are provided with aligned openings for the reception of a screw 15, the head portion of which has screw-threaded engagement with the opening in the arm 11. Preferably the arm 12 has a downwardly extending boss B concentric with the opening for the screw 15 and this boss is adapted to seat in a socket in the shuttle body and to cooperate with the screw 8 in holding the block 7 firmly in position.

15 On the arm 12 I preferably mount a wear-resistant tension element 16 (Fig. 5). Preferably this tension element consists of a relatively thin plate of sheet steel, heat treated to make it wear resistant, and having a down-turned flange 17 at its left side (as viewed in Fig. 4,) said flange also extending along the front edge of this tension element. The flange is preferably smoothly rounded as shown at 18 (Fig. 5) to avoid wear or cutting of the yarn and at the same time to form a flaring throat to assist in entrance of the arm between it and the upper tension element. One of the two elements, for example the element 16 is preferably provided with spacer means, for example two or more bosses 19 (Fig. 6) adapted to engage the opposed plate and at this point to hold the plates in definite spaced relation as hereafter described. The plate 16 is provided with an opening 20 through which the screw 15 passes, and its rear edge is substantially straight and adapted to engage the substantially flat rear face of the recess 14.

20 The upper tension element 21 preferably consists of a substantially flat piece of hard sheet steel having an opening for the passage of the screw 15 and being provided at its left side (as viewed in Fig. 4) with an upstanding flange 22 which also extends around the front edge of the tension element. This flange is smoothly rounded as indicated at 23, (Fig. 3) cooperating with the rounded portion 18 of the lower tension element to form a flaring entrance throat for the yarn. Preferably the lower plate 16 extends forwardly (Fig. 3) a slight distance beyond the forward edge of the plate 21 to insure entrance of the yarn between them.

25 At the forward edge of the plate 21 the flange 22 is preferably extended upwardly in the form of a lip, 24 preferably bent more or less to a curvature substantially concentric with the rear edge of lower plate 16, is disposed behind the downwardly curved portion 13 of the fixed arm 11. This upper ten-

sion element is also furnished with a substantially straight rear edge engaging the flat rear wall 25 of the recess 14 and, like the plate 16 is prevented from turning upon the post 15 as an axis by the engagement of its rear edge with the wall 25. A spring 26 encircles the screw 15, bearing at its lower end against the tension member 21 and at its upper end against a shoulder on the screw. The tension of the spring may thus be adjusted by turning the screw; preferably the arm 11 is split providing a narrow slit extending into the bore in which the screw 15 is disposed and the resiliency of the metal tends to pinch the screw 15 and thus to hold it in adjusted position.

30 In the arrangement shown in Fig. 7, the block 7^a with its arms 11^a and 12^a, the screw 15^a and the spring 26^a correspond to similar parts shown in Fig. 3, but in this device the lower removable wear-resistant member 16 above described is omitted and the arm 12^a itself constitutes the lower tension element, cooperating with the upper tension element 22^a to tension the thread passing between them. While this arrangement may be used under some circumstances, it is somewhat difficult to harden the arm 12^a sufficiently to withstand the cutting action of the thread without unduly hardening other parts of the 95 block, so that it may be necessary to replace the entire block at relatively frequent intervals, whereas in the preferred form of the device it is merely necessary to exchange the removable tension element 16 for a new one. 100

35 In Figs. 4 and 8 I have shown the tension block 7 associated with an elongate member 28 provided at one end with upcurved fingers 29 and 30 constituting a yarn delivery eye. The member 28 is provided at a suitable point 105 with an aperture for the passage of the boss B. The member 28 with its thread eye is disposed in a suitable channel at the bottom of the thread delivery passage and is held therein in operative position by means of the block 7 which rests upon it, the delivery eye comprising the fingers 29 and 30 then taking the place of the parts 5^a of Fig. 2.

40 As shown in Fig. 1, I preferably provide a yarn guide pin 27 at such a point in the 110 shuttle body that the yarn Y, extending through the arm delivery passage, moves in a substantially straight line between the pin 27 and the delivery eye 5, so that it follows a rectilinear path in its passage between the 115 tension elements.

45 In threading the shuttle, the yarn is drawn forwardly and then laterally through the threading slot 6 and as it drops down into the yarn delivery passage it slips smoothly 120 over the curved outer face of the member 13, thence down over the exposed portion of the lip 24 and the curved surface 23 into the flaring throat between the tension plates, and as it is drawn into the thread delivery eye 5 it 125

enters between the plates, raising the upper plate against the tension of the spring 26. Since the plates are spaced apart by the bosses 19 a distance substantially equal to the spacing produced by the interposed yarn, the plates remain substantially parallel during operation, thereby producing accurate and uniform tension.

It should be noted in this connection that when the yarn enters between the plates, the upper plate tends to swing about the rear edge of plate 16 as an axis, the lip 24 sliding up behind the part 13, and except for the provision of the lugs 19, the upper tension member would tend to take an inclined position, thus pressing more strongly upon the rear part of the yarn than upon the forward part thereof. With the present arrangement the parallel disposition of the plates results in a more uniform distribution of the pressure on the yarn and thus a more certain action. Obviously the spacer members 19 may be carried by the upper tension element or may be separate members secured in position in any desired manner. Likewise, while it is preferred to make the rear wall 25 of the recess 14 flat and to give the tension elements corresponding straight rear edges, it is obvious that other cooperating surfaces may be provided such as will prevent rotation of the tension elements about the pin 15.

The device thus provided is very simple in construction, easy to make and install, and it provides very uniform tension. It does not interfere with the threading operation, and the thread-engaging elements may readily be replaced when worn.

While I have herein disclosed a desirable embodiment of the invention, it is to be understood that various changes in shape, proportion and relative arrangement of parts may be made without departing from the spirit of the invention.

I claim:

1. A tension device of the class described comprising a lower tension element and a fixed arm spaced from and overhanging said element, said arm terminating in a downwardly directed portion tapering to a thin edge, and an upper tension element movable toward and from the lower tension element and having a yarn guiding portion extending upwardly and behind the tapering portion of said overhanging arm.

2. A tension device of the class described comprising a lower tension element, a fixed arm overhanging the lower tension element, the outer end of said arm being directed downwardly and having smoothly curved inner and outer surfaces merging in a thin lower edge, and an upper tension element movable toward and from the lower tension element, said upper tension element having a lip provided with a smooth outer surface normally con-

tacting with the thin lower edge of said overhanging arm.

3. In combination with a shuttle having a bobbin chamber and a threading slot leading forwardly and laterally therefrom and a cavity opening into said slot, a block seated in said cavity with one of its faces exposed to the slot, said exposed face of the block having an opening, and relatively movable tension members carried by the block and exposed at said opening.

4. In combination with a shuttle having a bobbin chamber, a thread delivery passage extending forwardly from the chamber and laterally to a delivery eye at the side of the shuttle body, a threading slot extending downwardly into said delivery passage, and a cavity opening laterally into said slot and delivery passage, a block seated in said cavity, said block having a recess opening at opposite sides into the thread delivery passage and at its front into the threading slot, respectively, and relatively movable tension elements within the cavity in the block, said elements having edges exposed at the sides and front of the block, the tension elements having smoothly rounded portions defining a flaring throat to facilitate entry of yarn drawn downwardly into the delivery passage and out through the delivery eye.

5. A tension device of the class described comprising a block having a body portion and arms projecting forwardly from the upper and lower parts thereof, the upper arm terminating in a downwardly curved guard tapering to a thin edge, a tension element comprising a plate having smoothly curved upwardly directed flanges at its front and at least one side edge, the front flange extending upwardly behind the tapering guard, and spring means tending to move the upper tension element toward the lower arm of the block.

6. In combination with a shuttle having a threading slot therein and a cavity opening into the threading slot, a tension block seated in said cavity, said block having a smoothly rounded surface opposed to the wall of the threading slot but spaced therefrom, a pair of relatively movable tension elements within a recess in the block, said elements having edges exposed through an opening in the block, and means extending upwardly from the upper tension element and providing a surface substantially continuous with the rounded surface of the block.

7. A tension device for shuttles comprising upper and lower tension elements, means resiliently urging one element toward the other, a fixed arm overhanging the lower tension element, the outer end of said arm extending downwardly, the upper tension element being capable of swinging about the rear portion of the lower tension element as a fulcrum, the upper element having at its

forward edge an upwardly directed lip curved on an arc substantially concentric with the rear edge of the lower element, the inner surface of the downwardly extending part of the overhanging arm being curved to accommodate upward swing of the lip of the upper tension element.

8. A tension device of the class described comprising a block adapted to be seated in a shuttle body, said block having a recess therein, the recess having a substantially flat wall, a pair of tension elements within the recess, each element having a substantially straight edge engaging said flat wall, each element having an opening therethrough, and a fixed post extending through said openings, the engagement of the straight edges of said elements with the wall of the recess preventing rotation of the elements about the post.

20. 9. A yarn tension device for shuttles comprising a block adapted to seat in a cavity in a shuttle body, tension elements carried by the block, the block having a downwardly projecting boss adapted to enter a socket in the shuttle body, an elongate member having a thread guide eye at its end, said elongate member having an opening for the reception of said boss whereby the block with its boss holds the elongate member with its thread eye in operative position in the shuttle body.

10. A tension device for shuttles comprising upper and lower tension plates, means resiliently urging one plate toward the other, and spacer means between the plates at a point remote from the path of the yarn passing between them to insure substantial parallelism of the plates when in operation.

11. A tension device for shuttles comprising upper and lower tension plates, means resiliently urging one plate toward the other, said resilient means acting at a point intermediate the edges of the plates, the yarn path being at one side of said resilient means, and spacer means carried by one plate at the opposite side of said resilient means from the yarn path, said spacer means holding the plates apart a distance substantially equal to the spacing produced by an interposed yarn whereby to maintain the plates in parallel relation during operation.

12. A tension device comprising a block adapted to seat in a cavity in a shuttle body, said block having a bore adjacent to one side for the reception of an anchoring bolt, the block having a recess at one side of said bore, relatively movable tension elements at the lower part of said recess, a spring in the recess bearing against the upper tension element, a screw engaging a threaded bore in the block, said screw having a shoulder engaging the spring whereby to adjust the tension of the latter, the block having means for retaining the screw in adjusted position.

13. A tension device comprising a part provided with a screw-threaded bore, said

part being split to provide a narrow slot leading into said bore, a screw engaging said part and retained in adjusted position therein by the resilient pinching action of the slotted part, a pair of relatively movable tension elements, and a spring engaging one of said elements, the spring also engaging said screw thereby permitting adjustment of the spring tension.

Signed by me at Lawrence, Mass., this 8th day of October, 1928.
